UNITED STATES PATENT OFFICE.

JACOB H. PIVONKA, OF TIMKEN, KANSAS.

SHELL.

1,146,950.

Specification of Letters Patent. Patented July 20, 1915.

Application filed April 8, 1915. Serial No. 19,998.

To all whom it may concern:

Be it known that I, JACOB H. PIVONKA, a citizen of the United States, residing at Timken, in the county of Rush and State of Kansas, have invented a new and useful Shell, of which the following is a specification.

The present invention appertains to explosive shells or projectiles, such as are used in warfare, and aims to provide a novel and improved shell of the shrapnel type and embodying a plurality of bombs or secondary shell which are scattered over a considerable area when the shell explodes, and which are in turn exploded so that the damage caused or the protection afforded by the shell may be considerably greater than that of an ordinary shrapnel shell.

It is the object of the invention to provide novel bombs or secondary shells assembled within the main shell or cylinder in a unique manner whereby the bombs will be effectively scattered when the shell explodes, and whereby the bombs will be scattered over a considerable area and will be exploded shortly after the explosion of the shell proper so that the fragments of the bombs or secondary shells will in turn be scattered over a considerable area.

It is also within the scope of the invention to provide a shell having the features above noted, and which is comparatively simple and inexpensive in construction, as well as being efficient and thoroughly practical in use.

With the foregoing and other objects in view which will appear as the description proceeds, the invention resides in the combination and arrangement of parts and in details of construction hereinafter described and claimed, it being understood that changes in the precise embodiment of the invention herein disclosed can be made within the scope of what is claimed; without departing from the spirit of the invention.

The invention is illustrated in the accompanying drawings, wherein:

Figure 1 is a side elevation of the improved shell, a portion thereof being shown in section, with the section taken on the line 1-1 of Fig. 2. Fig. 3 is a cross section of the shell taken on the line 2-2 of Fig. 1. Fig. 3 is a perspective view of one of the bombs.

In carrying out the invention, the shell comprises a cylinder or jacket 1 which is

hollow or chambered in the usual manner, and which is provided with a suitable time fuse whereby the shell will be set off or fired at a predetermined time or distance from the 60 cannon or ordnance employed for projecting or shooting the shell. The cylinder or body 1 is of usual formation, and is provided with a pointed forward end or nose, and the shell may be provided with the features of an ordinary shrapnel shell with respect to the time fuse and cylinder or jacket 65 construction.

In carrying out the invention, a plurality of bombs or secondary shells 2 are disposed or nested within the cylinder or jacket 1 and each of these bombs embodies a hollow case 3 of segmental-shaped cross section. The bombs 2 are arranged in groups at longitudinally spaced points within the cylinder 1, there being preferably three bombs in each annular group. The corners of the bombs are beveled.

The case 3 of each bomb is provided with an outer curved wall 4 conforming to the 80 curvature of the periphery of the cylinder 1, and fitting snugly thereagainst, and the case 3 is provided with a flat inner wall 5 opposite wall 4. The case 3 is also provided with oblique or angularly arranged 85 walls 6 between the outer and inner walls 4 and 5, respectively, and which diverge from the wall 5 to the wall 4. The inner walls 5 of the bombs provide a longitudinal chamber therebetween which is of triangular 90 cross section, and the said chamber has portions extending between the beveled corners of the respective bombs. The said chamber is filled with a high explosive or explosive charge 7 which is disposed compactly between the bombs to hold the bombs in place 95 against the periphery of the cylinder. Each of the bombs 2 is provided with a high explosive or explosive charge 8 within its case 3, and may also be provided with missiles 9 100 therein. The inner walls 5 of the bombs are provided with suitable fuses 10, which are arranged to be ignited when the explosive 7 is ignited, and which after a few seconds or short period of time will ignite the explosive charges within the bombs. The fuses 10 may be of any suitable type and need not be illustrated or described in detail.

The bombs may be conveniently placed within the cylinder during the construction 110 of the shell and the main explosive charge. 7 may be introduced into the cylinder dur-

ing the placing of the bombs therein, and whereby the bombs and explosive charge 7 will be held in place properly. It will be noted that the bombs being of segmental 5 shape may be fitted in a compact and convenient arrangement within the cylinder, and furthermore when the explosive charge 7 is ignited, it will effectively separate the bombs for scattering them and breaking the 10 body 1 into fragments.

When the shell is shot from the cannon or ordnance, the time fuse (not shown) which has been properly set, will ignite the main explosive charge 7 at a predetermined 15 time or distance from the point of discharge, the charge 7 being ignited will not only break the cylinder 1 into fragments, but will also scatter the bombs in various directions and over a considerable area. 20 The charge 7 being ignited will also ignite the fuses 10 of the bombs and after the bombs have been scattered to the desired extent, the explosive charges 8 of the bombs themselves will be ignited and the bombs 25 will be broken open into fragments. Thus, the fragments of the cylinder or body not only scatter and serve as an effective means of destruction, but the fragments of the bombs will also scatter and materially in- 30 crease the danger wrought. If the missiles 9 are employed in the bombs the missiles

will also be scattered when the bombs are exploded, for increasing the efficiency of the shell.

The present shell will possess a high degree of efficiency for offensive or defensive operations, and will produce damaging effect superior to the ordinary shrapnel shell, since the fragments of the present shell will be of greater number and will be scattered 35 throughout a greater area. 40

Having thus described the invention, what is claimed is:—

In an explosive shell, a cylinder, a plurality of annular groups of bombs within 45 the cylinder, each bomb comprising a segmental-shaped case containing an explosive charge and missiles, the outer walls of the bomb cases being curved to fit snugly against the cylinder, the inner walls of the bomb 50 cases being flat, and the corners of the said cases being beveled, fuses carried by the inner walls of the bombs, and a main explosive charge within the cylinder between the bombs. 55

In testimony that I claim the foregoing as my own, I have hereto affixed my signature in the presence of two witnesses.

JACOB H. PIVONKA.
